CLAIM

The ornamental design for an accessory attachment rack, as shown and described.

DESCRIPTION

FIG. 1 is a front view of an accessory attachment rack showing our new design;

FIG. 2 is a side view thereof;

FIG. 3 is a side view thereof;

FIG. 4 is a rear view thereof;

FIG. 5 is a bottom view thereof;

FIG. 6 is a top view thereof;

FIG. 7 is a front perspective view thereof; and,

FIG. 8 is a rear perspective view thereof.

The uniform broken lines illustrate portions of the article and form no part of the claimed design. The dot-dash broken lines depict a boundary of the design.
